PUMPING APPARATUS

George E. Reagin, Tulsa, Okla.

Application May 24, 1937, Serial No. 144,397

11 Claims. (Cl. 103—221)

This invention relates to new and useful improvements in pumping apparatus.

One object of the invention is to provide an improved apparatus for pumping wells which is so arranged that the liquid or fluid within the well tubing above the apparatus may be drained or by-passed around the apparatus at any desired time.

An important object of the invention is to provide an improved pumping apparatus including a standing valve and a pump plunger having a travelling valve, with means for unseating the travelling valve and by-passing liquid around the standing valve to permit bleeding of the well tubing above the apparatus; said means being so constructed as not to interfere with the normal operation of the apparatus.

Another object of the invention is to provide an improved standing valve structure for a well pumping apparatus which includes a by-pass which is normally closed so as to permit normally opening and closing of the standing valve, the by-pass being arranged to be opened by the lowering of the pump plunger onto the standing valve, whereby liquid above the valve may drain thereby.

Still another object of the invention is to provide an improved plunger for a well pumping apparatus including a tubular mandrel having the usual travelling valve at its upper end, with an axial stem extending through the mandrel and adapted to engage the valve to hold the same unseated to allow bleeding of the tubing thereabove, said stem normally being out of engagement with the valve, whereby during the normal reciprocation of the plunger, the stem does not interfere with the operation of said valve.

A particular object of the invention is to provide an improved standing valve assembly removably mounted in the lower end of a working barrel and having a ball and seat adapted to operate in the usual manner; together with a valve cage enclosing the ball and slidably mounted on the assembly, said cage controlling the uncovering of bleeder parts located below the ball whereby the barrel above the ball may be drained of liquid with the ball in its seated position.

A construction designed to carry out the invention will be hereinafter described, together with other features of the invention.

The invention will be more readily understood from a reading of the following specification and by reference to the accompanying drawings, in

which an example of the invention is shown, and wherein:

Figure 1 is a view, partly in elevation and partly in section of the upper portion of a working barrel, showing a pump plunger, constructed in accordance with the invention therein.

Figure 2 is a continuation of Figure 1 and showing the lower portion of the working barrel with a standing valve, constructed in accordance with the invention mounted therein.

Figure 3 is a view similar to Figure 1, and showing the plunger lowered within the working barrel so as to engage the cage of the standing valve.

Figure 4 is a continuation of Figure 3 showing the position of the standing valve assembly when the lower end of the plunger engages said assembly.

Figure 5 is an elevation of the standing valve and its cage in a normal operating position.

Figure 6 is a view similar to Figure 5 showing the cage lowered so as to permit bleeding of the tubing or barrel above the valve.

Figure 7 is a horizontal cross-sectional view taken on the line 7—7 of Figure 1, and

Figure 8 is a horizontal cross-sectional view taken on the line 8—8 of Figure 2.

In the drawings, the numeral 10 designates a working barrel of a well pump, which barrel has its upper end connected to the lower end of a well tubing (not shown). The working barrel may be of any desired length and is of course disposed axially in the well in the usual manner.

The lower end of the barrel is externally screw-threaded as shown at 11 and a collar 12 is connected to this lower end. The collar extends below the working barrel and is provided with an annular ring 13 which is located at the central portion of the bore of said collar.

The ring has its inner surface beveled as shown at 14 so as to form a seat, whereby a standing valve assembly A may be supported thereon. It is noted that the collar 12 could be eliminated and the seat 14 formed as an integral part of the lower end of the working barrel. However, when the collar 12 is employed it is possible to connect the working barrel at a point intermediate the ends of the tubing string instead of suspending the same from the extreme lower end thereof. This might be advantageous in certain instances.

The standing valve assembly A includes a supporting collar or sleeve 15 which has its lower exterior surface beveled as shown at 15', and this bevel is complementary to the incline of the seat 14, whereby said collar or sleeve may engage

- said seat. The lower end of the bore of the collar 15 is screw-threaded so that if the working barrel is connected intermediate the tubing string, a tubular extension (not shown) may be connected 5 to the lower end thereof. The upper end of the bore of the collar 15 is also internally screw-threaded to receive the lower end of a tubular mandrel 16 which extends upwardly from the collar.
- 10 An external annular shoulder 17 is formed on the collar 15 and an elastic packing element 18 rests on the shoulder 17 and engages the bore 10' of the working barrel 10, whereby the space between the collar and the barrel is packed off.
- 15 A retaining sleeve 19 is threaded onto the upper external end of the collar 15 and has its lower end engaging the packing element 18 to hold the same in position on the collar. The sleeve 19 extends upwardly from the collar 15 and has a bore of 20 such diameter that an annular space 20 is formed between said sleeve and the outer surface of the mandrel 16. An internal annular shoulder 21 is formed near the upper end of the sleeve 19, as is clearly shown in Figure 2.
- 25 The exterior of the mandrel 16 is enlarged at its upper end to form a beveled annular shoulder 22 and this shoulder is located at point above the upper end of the sleeve 19. A valve seat or ring 23 is supported in an annular recess 24 provided in the upper end of the mandrel. A ball 25 is adapted to engage the seat 23 to close the bore of the mandrel and the bore of the collar 15, whereby a flow therethrough is prevented. A cylindrical valve cage 26 encloses the ball 25 and has its upper end closed by a cap or head 27 which is threaded thereinto. The cap 27 is provided with an axial opening 28 which is internally screw-threaded so as to receive a suitable lowered tool (not shown), as will be explained.
- 35 The lower end of the valve cage 26 surrounds the upper end of the mandrel 16 and the bore of said cage is formed with an internal annular beveled shoulder 29, the inclination of which is complementary to the annular bevel 22 of the mandrel. The extreme lower end of the cage is disposed within the upper end of the sleeve 19 and manifestly said cage is slideable within the upper end of said sleeve and moves with relation to the upper end of the mandrel. A coiled spring 30 surrounds the mandrel 16 and is disposed in the annular space 20 between said mandrel and the sleeve 19, and this spring is confined between the lower end of the valve cage 26 and the upper end of the collar 15. The spring normally exerts its pressure to urge the valve cage 26 upwardly, whereby the annular shoulder 29 of said cage is in engagement with the exterior beveled shoulder 22 on the mandrel.
- 45 The downward movement of the valve cage 26 is limited by the lower end of said cage striking the internal shoulder 21 within the sleeve 19, and also by an external shoulder or offset 26' on the cage 26 striking the upper end of said sleeve 19.
- 50 The valve cage 26 is formed with a plurality of vertical slots 31 which extend from a point near the upper end of said cage to a point near the lower end thereof.
- 55 When the valve cage is in its raised position 70 with its internal beveled shoulder 29 engages the beveled shoulder 22 of the mandrel, the lower ends of the vertical slots 31 are located in a plane above the shoulder 22 on the mandrel, as clearly shown in Figure 5. A plurality of inclined ports 32

16 and have their outer ends terminating in the external beveled shoulder 22 of said mandrel. The inner ends of said ports, of course, communicate with the bore of the mandrel 16. Manifestly, when the valve cage is in its raised position, being held so by the coiled spring 30, (Figures 2 and 5), the engagement of the internal shoulder 29 of the cage with the external shoulder 22 of the mandrel covers the ports to prevent a flow therethrough. Since the lower ends of the vertical slots 31 of the valve cage 26 are located in a plane above the ports 32, a flow from the slots to the ports is impossible.

When the valve cage 26 is lowered with relation to the mandrel under tension of the spring 30, the beveled shoulder 29 of said cage will move away from the shoulder 22 of the mandrel, as shown in Figures 4 and 6. This movement of the cage will uncover the ports 32, whereby a flow from the bore of the mandrel into the interior of the cage 26 may occur. At the same time that the shoulder 29 of the cage leaves the shoulder 22, the lower ends of the slots 31 will move downwardly into alignment with the ports 32. Therefore any liquid or fluid above the cage 26 can enter the cage through the slots 31 and from this point will flow through the ports 32 and downwardly through the mandrel 16, collar 15 and then to the bottom of the well. Thus, it will be seen that when the cage 26 is in its lowered position, liquid may flow from above the valve assembly A and by-pass the ball 25 which is in its seated position, and may escape downwardly through the mandrel and collar.

30 A plunger assembly B is mounted to reciprocate vertically in the working barrel 10 above the standing valve assembly A. This plunger assembly includes a tubular mandrel 35 which has a valve seat 36 mounted at its upper end. A ball 31 is adapted to engage the seat and is enclosed 35 by a valve cage 38 which is threaded onto the upper end of the mandrel and which holds the valve seat or ring 36 in place. The valve cage has vertical slots 39 therein, whereby when the valve 37 is unseated fluid may flow upwardly 40 through the bore of the mandrel outwardly through the slots 39 and into the barrel 10 above the plunger. A suitable connecting collar 40 is fastened to the upper end of the cage 38 and this collar in turn is carried by the usual pump rod 41.

45 The mandrel 35 is externally shouldered at 42 and a plurality of packing cups 43 which are spaced from each other by spacing collars 44 surround said mandrel beneath this shoulder. The cups 43 are held on the mandrel by a retaining cap or head 45 which is threaded onto the lower end of the mandrel 35. The bore 45' of the cap is larger than the bore of the mandrel, and a plurality of radially extending slots 46 establish communication between the bore of the cap 45 and the interior of the working barrel 10. The extreme lower end of the bore 45' is reduced so as to form an internal annular shoulder 47 within the cap.

55 An elongate stem 48 extends axially through the bore of the mandrel 35 and is formed with a conical flange 49 through its lower end. This flange is arranged to engage the internal shoulder 47 of the cap and a guide rod 50 depends 60 from the flange 49, extending through the reduced portion of the bore of the cap 45. The extreme lower end of the guide rod 50 has a collar 51 threaded thereon, and a coiled spring 52 which surrounds the rod is confined between the 70

collar 51 and the underside of the cap 45. The spring 52 exerts its pressure at all times to urge the rod 50 and stem 48 downwardly with relation to the mandrel 35 and cap 45, whereby the annular flange 49 is held seated on the shoulder 47. When said flange is resting on said shoulder, the upper end of the stem 48 is spaced from the lower end of the ball 37 when the ball is in its seated position, as shown in Figure 1. An upward movement of the stem 48 would, of course, cause said stem to strike the ball 37 and lift said ball from its seat 36, as shown in Figure 3, and so long as said stem remains in its raised position, the ball 37 is held in an unseated position. When so unseated, fluid from above the plunger assembly B may flow downwardly through the slots 39 of the cage 38, and then downwardly through the bore of the mandrel 35, from where it may escape through the radial slots 46 in the cap member 45 and to the interior of the working barrel 10 below the plunger assembly.

In operation, the standing valve assembly A is first lowered into the working barrel by a cable, rod or other lowering device until the beveled portion 15' at the lower end of the supporting collar 15 rests on the beveled seat 14 provided within the collar 12. The annular space between the assembly A and the working barrel is of course packed off by the elastic packing element 18. The lowering device (not shown) is then disconnected from the valve cage 26 of the assembly A and the parts are then in the position shown in Figure 2 with the ball 25 engaging the seat 23 and the valve cage 26 held in its uppermost position by the coiled spring 30. At this time the internal annular beveled shoulder 29 of the cage 26 is in engagement with the external beveled shoulder 22 of the mandrel 16, whereby the radial ports 32 which extend through the mandrel are covered or closed. Therefore, any liquid which may be above the assembly A will act downwardly against the ball 25 through the slots 31 to hold said ball seated. It is noted that the coiled spring 30 is of sufficient strength to prevent the liquid above the assembly from moving the cage downwardly.

The plunger assembly B is then attached to the lower end of the pump rod 41 and is lowered downwardly through the tubing into the working barrel 10. The stroke of the pump plunger, of course, varies in each particular well and as said rods are reciprocated vertically, the plunger is also reciprocated in the working barrel above the standing valve assembly A. The plunger and standing valve normally operate in the usual manner, that is, upon the down stroke of the plunger the valve 37 at the upper end of the mandrel 35 is unseated to permit liquid to flow upwardly through the slots 46 in the cap member 45, then through the bore of the mandrel 35 and finally out through the slots 39 into the interior of the working barrel 10 above the plunger. As the plunger is moving downwardly, the pressure of the liquid against the ball 25 of the standing valve assembly A holds said valve seated, and said valve acts as a check valve to prevent flow of the liquid downwardly thereby upon said stroke. As the plunger moves on its upstroke, the suction created thereby unseats the ball valve 25 and draws liquid from below the standing valve assembly A, upwardly through said assembly and into the working barrel above the valve 25. During the upward movement of the plunger assembly B, the valve 37 is seated and serves to raise the liquid thereabove upwardly in the tubing.

This operation of the valves 25 and 37 is common in all pumping equipment.

It is noted that the stroke of the pump plunger assembly B is such that when in its lowermost position or at the bottom of its stroke, the collar 51 on the lower end of the assembly B is spaced above the cap 21 at the upper end of the valve assembly A, whereby as the plunger reciprocates, it never touches the lower valve assembly A. During the normal reciprocation or operation of the plunger B, the parts are in the position shown in Figure 1, that is, the spring 52 is holding the stem downwardly so that its flange 49 is engaging the internal seat 47 of the cap member 45.

When it is desired to relieve the load above the pump plunger assembly B or for any reason it is desired to drain the tubing and working barrel above the plunger or above the standing valve assembly A, it is only necessary to lower the assembly B so that the collar 51 at its lower end strikes the top of the cage 26. As the weight of the plunger assembly B is placed on the cage 26, said cage is forced downwardly under tension of the spring 30. As this occurs, the internal annular shoulder 29 leaves the external annular shoulder 22 of the mandrel 16, whereby the ports 32 are uncovered and the vertical slots 31 in the valve cage 26 are moved into registration with said ports.

When the cage 26 reaches its lowermost limit and can move no further, the weight of the assembly and pump rod is placed entirely on the collar 51, rod 50 and stem 48. Since the collar 51 is resting against the top of the cage 26, it can undergo no further movement and therefore continued downward movement of the assembly B, causes the mandrel 35 and cap member 45 to move downwardly with relation to the stem under tension of the coiled spring 52. This downward movement of the mandrel with relation to the stem 48, causes the ball valve 37 to engage the upper end of said stem which halts the movement of the valve 37. As the mandrel continues its downward movement, the seat 36 leaves the ball 37, whereby the bore of the mandrel is opened.

The parts are then in the position shown in Figures 3 and 4 and the liquid or fluid in the working barrel and tubing above the plunger may flow downwardly through the slots 39, bore of the mandrel 35 and outwardly through the slots 46 into the interior of the working barrel below the plunger assembly B. From this point the liquid or fluid may flow through the slots 31 of the valve cage 26 and then through the ports 32 and downwardly through the mandrel 16 and collar 15 of the standing valve assembly A. Thus, it will be seen that all of the liquid in the tubing above the pumping apparatus may be drained downwardly to the bottom of the well. By lifting up on the plunger assembly B, the parts will again assume their normal operating positions as shown in Figures 1 and 2, the action being entirely automatic.

The apparatus needs no adjustment and so long as the collar 51 at the lower end of the plunger assembly B does not touch or engage the upper end of the cage 26, it is impossible for fluid or liquid above either of the assemblies A or B to drain downwardly thereby. The bleeding means 65 is therefore arranged so that under normal conditions it does not in any way interfere with the operation of the pumping equipment. The size of the bleeder ports 32 in the mandrel 16 of the assembly A may of course be varied in size and 70 75

it is not necessary that they be inclined as shown in Figure 2. Since it is only necessary to lower the weight of the assembly B and pump rod 41 onto the cage 26 in order to permit bleeding of the 5 tubing, it is evident that such bleeding may be accomplished with a minimum amount of time or trouble. If the pump plunger B should become overloaded, that is, should too much liquid be placed above the plunger, it is only necessary to 10 lower said plunger sufficiently for the collar 51 to strike the cage 25. As explained, this will cause a downward movement of the valve cage 26 and will also halt movement of the stem 48 to permit the mandrel 35 to move downwardly with relation thereto so that the valve 37 is unseated to permit a drain of the liquid from thereabove.

What I claim and desire to secure by Letters Patent is:

1. A pumping apparatus including, a standing 20 valve assembly supported within a working barrel, a plunger assembly arranged to reciprocate in the barrel above the standing valve assembly and having a travelling valve mounted thereon, both valves being arranged to permit an upward flow 25 of fluid through the assemblies and to prevent a down flow therethrough, and means for unseating the travelling valve and means for bypassing the fluid around the standing valve to allow a downward flow of the fluid through the 30 assemblies.

2. A pumping apparatus including, a standing 35 valve supported in a working barrel, a pump plunger arranged to reciprocate within the barrel above the standing valve and spaced from the standing valve when at the end of its downstroke, a travelling valve mounted on said plunger, said valves being arranged to permit an upward flow and to prevent a downward flow of liquid through the barrel, and means actuated by the engagement 40 of the plunger with the standing valve for unseating the travelling valve and means for bypassing liquid around the standing valve to permit a down flow of fluid through the working barrel.

45 3. A pumping apparatus including, a standing valve supported in a working barrel, a pump plunger arranged to reciprocate within the barrel above the standing valve and spaced from the standing valve when at the end of its downstroke, a travelling valve mounted on said plunger, said valves being arranged to permit an upward flow and to prevent a downward flow of liquid through the barrel, means actuated by the engagement 50 of the plunger with the standing valve for unseating the travelling valve and means for bypassing liquid around the standing valve to permit a down flow of fluid through the working barrel, and means for automatically permitting the 55 travelling valve to seat and for closing the by-pass when the plunger is disengaged from the standing valve.

4. A pumping apparatus including, a standing 65 valve assembly supported in a working barrel and comprising a valve for permitting an up flow and preventing a down flow of fluid through the barrel, a pump plunger normally reciprocating in the barrel above the standing valve assembly and arranged to engage said assembly, and means actuated by the engagement of the plunger for bypassing fluid around the valve for permitting a down flow of fluid past said valve.

5. A pumping apparatus including, a standing 70 valve assembly supported in a working barrel and comprising a valve for permitting an up flow and preventing a down flow of fluid through the bar-

rel, a pump plunger normally reciprocating in the barrel above the standing valve assembly and arranged to engage said assembly, means actuated by the engagement of the plunger for bypassing fluid around the valve for permitting a down flow of fluid past said valve, and means for automatically closing said by-pass when the plunger disengages the assembly. 5

6. A pumping apparatus including, a standing 10 valve assembly supported in a working barrel and comprising a valve for permitting an up flow and preventing a down flow of fluid through the barrel, a pump plunger normally reciprocating in the barrel above the standing valve assembly and arranged to engage said assembly, a travelling 15 valve carried by said plunger and arranged to permit upward flow and prevent a downward flow therethrough, and means actuated by the engagement of the plunger for unseating the travelling valve and means for bypassing fluid around the 20 standing valve to permit a down flow of fluid past the valves.

7. A pumping apparatus including, a standing 25 valve assembly supported in a working barrel and having a tubular mandrel, a valve at the upper end of the mandrel for permitting an upward flow and for preventing a downward flow of liquid through the mandrel, said mandrel having a plurality of by-pass ports located below the valve, a cage slidable on the mandrel 30 and enclosing the valve and normally in a raised position covering the by-pass ports, and a pump plunger reciprocating within the working barrel above the standing valve and arranged to move downwardly to engage the cage and slide the 35 same on the mandrel, whereby the by-pass ports are uncovered and liquid above the standing valve may flow downwardly past the valve and through the mandrel.

8. A pumping apparatus including, a standing 40 valve assembly supported in a working barrel and having a tubular mandrel, a valve at the upper end of the mandrel for permitting an upward flow and for preventing a downward flow of liquid through the mandrel, said mandrel having 45 a plurality of by-pass ports located below the valve, a cage slidable on the mandrel and enclosing the valve and normally in a raised position covering the by-pass ports, a pump plunger reciprocating within the working barrel above 50 the standing valve and arranged to move downwardly to engage the cage and slide the same on the mandrel, whereby the by-pass ports are uncovered and liquid above the standing valve may flow downwardly past the valve and through 55 the mandrel, a travelling valve carried by the plunger and arranged to permit an upward flow and prevent a downward flow of liquid through the plunger, and means actuated by the engagement of the plunger with the cage for unseating 60 the travelling valve when the by-pass around the standing valve is opened, whereby liquid above the plunger may drain downwardly therethrough.

9. A pumping apparatus including, a standing 65 valve assembly supported in a working barrel and having a tubular mandrel, a valve at the upper end of the mandrel for permitting an upward flow and for preventing a downward flow of liquid through the mandrel, said mandrel having a plurality of by-pass ports located below 70 the valve, a cage slidable on the mandrel and enclosing the valve and normally in a raised position covering the by-pass ports, a pump plunger reciprocating within the working barrel above 75 the standing valve and arranged to move down-

wardly to engage the cage and slide the same on the mandrel, whereby the by-pass ports are uncovered and liquid above the standing valve may flow downwardly past the valve and through the mandrel, a travelling valve carried by the plunger and arranged to permit an upward flow and prevent a downward flow of liquid through the plunger, means actuated by the engagement of the plunger with the cage for unseating the travelling valve when the by-pass around the standing valve is opened, whereby liquid above the plunger may drain downwardly therethrough, and means for automatically reseating the travelling valve and closing the by-pass when the plunger disengages the cage.

10. A pumping apparatus including, a standing valve assembly supported in a working barrel and having a tubular mandrel, a valve at the upper end of the mandrel for permitting an upward flow and for preventing a downward flow of liquid through the mandrel, said mandrel having a plurality of by-pass ports located below the valve, a cage slideable on the mandrel and enclosing the valve and normally in a raised position covering the by-pass ports, a pump plunger reciprocating within the working barrel above the standing valve and arranged to move downwardly to engage the cage and slide the same

on the mandrel, whereby the by-pass ports are uncovered and liquid above the standing valve may flow downwardly past the valve and through the mandrel, a travelling valve carried by the plunger and arranged to permit an upward flow and prevent a downward flow of liquid through the plunger, and a spring-pressed stem actuated by the engagement of the plunger with the cage for unseating the travelling valve when the by-pass around the standing valve is opened, where- 10 by liquid above the plunger may drain downwardly therethrough.

11. A pumping apparatus including, a standing valve assembly supported in a working barrel and having a tubular mandrel, a valve at the upper end of the mandrel for permitting an upward flow and for preventing a downward flow of liquid through the mandrel, said mandrel having a plurality of by-pass ports located below the valve, a cage slideable on the mandrel and enclosing the valve, and a coiled spring normally holding the cage in its raised position covering said by-pass ports, downward movement of said cage under tension of the spring uncovering said ports to permit a down flow of fluid past the closed valve.

GEORGE E. REAGIN.
